UNITED STATES PATENT OFFICE.

GEORGE HOFFMANN, OF MUSCATINE, IOWA.

DESIGN FOR A CULINARY SCRAPER.

SPECIFICATION forming part of Design No. 24,178, dated April 2, 1895.

Application filed January 17, 1895. Serial No. 535,283. Term of patent 14 years.

To all whom it may concern:

Be it known that I, GEORGE HOFFMANN, a citizen of the United States, residing at Muscatine, in the county of Muscatine and State of Iowa, have invented and produced a new and original Design for Culinary Scrapers, of which the following is a specification.

My design is for a culinary scraper, and is clearly shown in the accompanying drawings, in which—

Figure 1 is a perspective view of a scraper embodying my design. Fig. 2 is a longitudinal section, and Fig. 3 is a transverse section of the same.

The design consists in the configuration of the scraper plate shown in the drawings. Said design plate is slightly longer than wide. Its sides are parallel, one end is round, and the other straight but rounded off at the corners, and the entire edge of the plate is bent down or inclined as shown.

Having thus described my design, I claim—

The design for a culinary scraper substantially as herein shown and described.

GEORGE HOFFMANN.

In presence of—

FAY FITZGERALD,
T. R. FITZGERALD.
